UNITED STATES PATENT OFFICE.

CHARLES T. CAHILL, OF BOSTON, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON THE BOTTOMS OF BOOTS AND SHOES.

1,170,410.

Specification of Letters Patent.

Patented Feb. 1, 1916.

Application filed November 18, 1912. Serial No. 732,043.

To all whom it may concern:

Be it known that I, CHARLES T. CAHILL, a citizen of the United States, residing at Boston, in the county of Suffolk and State of Massachusetts, have invented certain Improvements in Machines for Operating Upon the Bottoms of Boots and Shoes, of which the following description, in connection with the accompanying drawings, is a specification, like reference characters on the drawings indicating like parts in the several figures.

This invention relates to machines for use in the manufacture of shoes and is herein shown by way of exemplification as embodied in a machine for breasting heels. In practice it is usual to remove the rough forward face or breast of a heel upon one machine and later as a distinct operation to im- 15 press upon some part of the sole of the shoe a numeral or other designation of size, quality or other characteristic necessary for the convenience of the manufacturer or seller or for the protection of the buyer. Obviously 20 this practice involves the expenditure of considerable time and labor in the performance upon the same portion of the shoe of two distinct and to some extent similar operations which could be saved by performing 25 the two operations together at the same time and by the use of the same machine.

The object of the present invention is therefore to provide means whereby the operation of impressing or imprinting a designation on the sole or other part of the shoe may be performed at the same time as, 35 and in conjunction with, another operation as, for example, the breasting of the heel.

An important feature of the invention 40 consists in the combination with a shoe support, of means for breasting the heel, and means for imprinting or stamping a design or designation upon some portion of the shoe bottom, for example, the shank, the 45 breasting means and the die of the stamping means being respectively positively and yieldingly operated. The operations of breasting and stamping preferably occur during the same operative cycle of the machine and may conveniently take place simultaneously and while the shoe is in the 50 same position on the support.

Another feature of the invention consists

in means, operated upon contact with the shoe shank, for releasing the breasting means 55 and the stamping means from their operating mechanism. In the construction shown, the breasting means is mounted on a slide which is reciprocated to effect the breasting operation, and means is provided for releasing the slide from its operating means when the breasting means has finished breasting the heel. The stamping means may be operated by the breasting means and, as shown, 60 is mounted upon the slide which carries the 65 breasting means. It follows, therefore, that the stamping means is released from its operating means simultaneously with the release of the breasting means.

Another feature of the invention consists 70 in means for operating the die or stamping means by power and releasing it when the die has yielded a predetermined amount. As shown, the die is resiliently connected with the power operated knife slide and extends 75 in advance of the knife. The stamp, therefore, comes in contact with the shank before the knife finishes the breasting cut, the resilient connection yielding a predetermined amount before the knife and the die 80 are simultaneously released after each has performed its work. The die, by reason of its resilient mounting, which preferably includes a stiff spring, may be brought into engagement with the work considerably before the knife has ceased to cut, the yielding means permitting the knife to finish the cut while insuring that the die shall be brought 85 with uniform and effective pressure against the work. Preferably, too, means is provided for adjusting the tension of the resilient backing of the die to adapt the pressure exerted thereby to the area of the die.

In the drawing, the figure is a side elevation of a breasting machine embodying this 95 invention.

The invention is herein shown as embodied in a machine of the same general type as that disclosed in an application for United States Letters Patent Serial No. 106 686,042, filed March 25, 1912, to which reference may be had for a fuller description of the general organization of the machine. The machine comprises a frame 2 in which a knife carrier 4 is arranged to slide vertically. The usual knife actuating slide is

mounted in a frame back of the knife carrier or slide 4 and is normally connected thereto. Automatic mechanism is provided for disconnecting the knife carrier 4 from the actuating slide upon contact of a bunter 6 with the shank portion of the shoe, when a knife 8 mounted on the carrier 4 has cut through the heel. The shoe is supported by a jack 10 and is located relatively to the 10 knife and held in position during the breast- 15 ing operation by a gage tread plate 12 which is depressed toward the heel by the usual connection to a treadle, not shown. The shoe stamping mechanism which is combined 20 with the breasting machine by this invention is mounted upon a bracket 14 which is bolted to the knife carrier on slide 4 at 16 for actuation thereby toward and from the shoe. The bracket 14 is shaped to provide bearings 25 at 18 and 20 for a rod 22 which is splined in the said bearings for vertical movement. The lower end of the rod 22 carries a block 24 on which a die 26 is mounted for movement about an axis 28 extending transversely of the shoe. As a further means of preventing rotation of the rod 22 about its axis, a pin 30 extends from the block 24 through a hole in the bracket 14. A portion of the rod 22 at 33 is threaded and is provided with 30 a capstan nut 34 between which and the bracket is located a strong helical spring 36. The spring 36 holds the rod 22 depressed with a clamp nut 38 which is threaded on the upper end of the rod in contact with the 35 bracket 14.

In the operation of the machine the shoe is placed upon the jack 10 which swings about a pivot near its lower end, not shown, and the shoe is swung beneath the plate 12 which is then depressed by the treadle against the 40 heel and the heel is located with respect to the forward edge of the plate which indicates the position of the cut to be made by the knife. The treadle is then further depressed to start the machine, whereupon the 45 knife carrier 4 carrying the bracket 14 is depressed. After the knife 8 has begun to cut the heel, but prior to the contact of the bunter 6 with the shank of the shoe, the die 26 comes into contact with the tread face of 50 the shank. Continued movement of the knife carrier forces die 26 into the leather, the spring 36 yielding, if necessary, to permit the knife to complete its stroke. Upon 55 the completion of the knife stroke the bunter 6 contacts with the shank and disconnects the knife carrier from its actuator whereupon the knife 8 and the die 26 return together to their normal position, as shown. The tread plate 12 is then released and the 60 shoe removed from the jack.

Having described my invention, what I claim as new and desire to secure by Letters Patent of the United States is:—

1. In a machine of the class described, 65 the combination of a shoe support, a re-

ciprocating slide, means for breasting the heel of a shoe, means for stamping the shank of the shoe, both said means being actuated respectively unyieldingly and yieldingly by said slide, and means operating 70 upon contact with the shoe shank for releasing the breasting means and the stamping means from actuation by the reciprocating slide.

2. A machine of the class described having, in combination, a work support for sustaining a shoe, a knife for breasting the shoe heel, operating means therefor, a die, connections between the die and the knife operating mechanism for effecting a die impression upon the outer face of the shoe bottom during the operating cycle of the breasting knife, and means for automatically effecting release of the knife and die simultaneously when the end of their 85 operative stroke is reached.

3. A shoe machine comprising positively actuated heel breasting mechanism and resiliently actuated stamping means arranged to operate respectively on the heel and on 90 the shank portion of a shoe, and a supporting jack for the shoe, said parts being so arranged that the heel may be breasted and the shank stamped while the shoe remains in the same position upon said support. 95

4. In a machine for operating upon shoes the combination of a shoe support, a slide mounted for reciprocation toward and from a shoe on said support, a bracket secured to the slide, a rod having bearings in said bracket, a die carried by the rod, a spring for resiliently holding the die carrying rod depressed in the bracket, means for actuating the slide to force the die upon the shoe, a breasting knife operated by said slide simultaneously with said die, and means for automatically releasing the slide from the actuating means when the said spring has yielded a predetermined amount. 100

5. A machine of the class described, having, in combination, a shoe support, a power actuated slide, a breasting knife mounted on said slide, a stamp resiliently carried upon said slide and arranged to contact with the shoe bottom when the slide is reciprocated, and means for releasing the stamp from power actuation when the slide has made a predetermined stroke relatively to the shoe bottom. 110

6. In a machine of the class described, 120 the combination of positively actuated heel breasting mechanism, resiliently actuated stamping means arranged to operate respectively on the heel and on the shank portion of a shoe, supporting means for the shoe, and means for effecting the operation of the breasting mechanism and the stamping means to breast the heel and stamp the shank. 125

7. In a machine of the class described, 130

the combination of a shoe support, positively actuated heel breasting mechanism, resiliently actuated stamping means, and means for effecting the operation of the 5
breasting means and the stamping means upon a shoe on said support during the same operative cycle of the machine.

8. In a machine of the class described, the combination of a shoe support, positively
10 actuated heel breasting mechanism, resiliently actuated stamping means, and means for effecting simultaneously the operation of the breasting means and the stamping means on a shoe on said support.
- 15 9. A shoe machine comprising positively actuated heel breasting mechanism, and resilient actuated stamping means arranged

to operate respectively on the heel and on the shank portion of a shoe, means for effecting adjustment to vary the effect of the 20
resilient actuation of the stamping means against the shoe, and a supporting jack for the shoe, said parts being so arranged that the heel may be breasted and the shank 25 stamped while the shoe remains upon said support.

In testimony whereof I have signed my name to this specification in the presence of two subscribing witnesses.
